A CORPORATION OF INDIANA.

ELECTRICAL APPARATUS.

REISSUED

Application filed December 23, 1922. Serial No. 608,703.

Our invention relates to electrical switches designed particularly for the regulation or control of electrical circuits, such as may be used in connection with heating, cooling or 5 alarm apparatus and systems.

The subject matter of this invention has reference to a device making use of a liquid electrical contactor tube, which comprises a container in which are mounted spaced electrodes adapted to be bridged by a body of mercury when the container is properly actuated.

Our invention makes use of an electrical contactor of the above mentioned type, 15 mounted in conjunction with heat or pressure responsive devices, such as curved pressure tubes and thermostatic elements. The pressure responsive or thermostatic element is designed to support and serve to actuate 20 the electrical contactor into or out of circuit closing position when a pressure or temperature change of a predetermined amount occurs.

More particularly our device refers to an 25 electric switch of this type in which the pressure or thermostatic element is unusually efficient, accurate and rapid in operation.

A further particular object of our invention is to provide a ready means for adjusting 30 the above type of device to operate at required predetermined conditions.

Another object of our invention is to produce a contactor tube of the above character, which may be readily mounted upon an 35 actuating device which has available a very small quantity of energy for actuating the contactor tube and which will require only a small change in pressure or temperature for its actuation.

40 A further object of our invention is to provide a switch device of the type indicated, that will be simple and economical to construct and which will possess great durability, even when subjected to mechanical abuse and when used in connection with 45 considerable quantities of electric current at substantial voltages.

Also further objects and advantages will appear from the following specification and 50 accompanying drawings, in which—

Figure 1 is an elevation view partly in section of my invention;

Fig. 2 is a sectional view taken on line 2—2 of Fig. 1;

Fig. 3 is a detail sectional view taken on line 3—3 of Fig. 2;

Fig. 4 shows a modification having a special type of casing;

Fig. 5 shows a modification having still another type of casing or housing;

Fig. 6 is a detail sectional view similar to Fig. 3 but showing a modified form of thermostatic element and contactor tube;

Fig. 7 is a front view of the device of Fig. 6; and,

Figs. 8 and 9 are detail sectional views of further modifications.

In a general way our invention, as shown in Fig. 1, comprises the liquid contactor tube 1 mounted upon a conical spiral thermostatic bi-metallic element 2, which in turn is pivotally mounted at 3 to the frame or support 4. A cover 5 serves to protect and enclose the device.

The tube 1 is constructed in a substantially toroidal form, preferably in the form of a torus. After the various parts in the tube are in place, the tube is evacuated and filled with an inert gas and sealed off through the tip 6. Electrodes 7 and 8 are inserted and sealed in the walls of the tube and may be formed of platinum or of Dumet wire covered or plated with casings of pure iron or the like metal which is unaffected by the arcing obtaining in the tube in the presence of the mercury and the mercury vapor. A body of conducting fluid 9, preferably mercury, may substantially fill the lower half of the container 1 and is normally in contact with the electrode 8. When the tube is tilted in the proper direction, the body of mercury 9 will come into bridging relation with the electrodes 7 and 8, thus closing an electrical circuit through the tube.

Since the tube is of toroidal form and is mounted to be tilted substantially about its geometrical axis, it will be noted, that the body of mercury 9 will remain practically stationary and of constant shape when the tube is tilted into or out of circuit making position. In other words, the body of conducting fluid 9, as well as the tube 1, retain a substantially stationary center of gravity when the tube is actuated. Hence it is obvious that very little energy is required either to initially move the tube or to return the tube to its normal position, since the parts remain practically balanced at all

times. In the former types of liquid contactor tubes, it has been necessary to displace a fairly large mass of heavy liquid in order to actuate the device. Such contactors have the further disadvantage that an appreciable temperature change is required to restore the parts including the body of conducting liquid to their normal position after once actuated.

- 10 The tube 1 is mounted concentric with the outer turn 2^a of spiral element 2 by means of detachable clips 10 comprising flexible bands of copper or similar material soldered or otherwise fixed to the spiral turn 2^a and clasped around the tube 1 at opposite and spaced points. It will be noted that this structure forms a very simple, compact and easily assembled arrangement of the contactor tube and the thermostatic element.
- 20 The spiral element 2 is preferably constructed of a bi-metallic ribbon composed of layers of any suitable metals or alloys, such as brass and nickel, and is wound substantially in the shape of a conical or helical spiral as shown. This form of winding has a particular advantage over the more usual simple spiral form in that a much larger portion of the surface area of the thermostatic ribbon or heat responsive element is directly exposed to the atmosphere and air currents. This is an important consideration when this type of device is used for accurate and rapid temperature regulation. This form of conical spiral mounting has a further advantage 35 in the present structure, in that it makes possible a more convenient arrangement of the lead wires to the contactor tube and permits the contactor tube to be flexibly mounted at a central position in the casing remote 40 from any of the fixed parts of the structure which would possibly hit against and break the glass tube.

The inner end of the spiral element 2 is mounted upon a pivoting shaft 3 which is 45 retained in a frame 4 by a nut 3^a and washer 3^b. A collar 11 surrounds the pivoting screw 3 and is fixed to the spiral element 2 by solder or by means of a screw 12.

The collar 11 is provided with an extension 13 which forms a handle for adjusting the angular position of the tube 1 and the spiral element 2 about its pivoting shaft 3. The handle 13 extends to the exterior of the casing and is provided with a pointer 14 55 co-operating with a calibrated scale 15 formed on an extension of the frame 4.

The electrodes 7 and 8 are connected in the circuit, respectively, by the flexible lead wires 16 and 17. The flexible wire 16 is attached to the outer end of the spiral element 2 so that the electric current flowing in the circuit will traverse this element for the particular purpose hereinafter described. From the spiral element 2 the circuit continues 60 through frame 4 to a binding post 19. The

flexible lead 17 is connected to a binding post 20. The binding posts 19 and 20 serve to connect the device to the desired external circuit.

The cover 5 is attached to the frame 4 by means of lugs 21 formed integral with the lower end of the frame 4 and by a lug 22 formed at the upper end of the frame 4 and engaged by a screw 23. Openings 24 are provided in the cover 5 for the purpose of permitting free circulation of air currents about the thermostatic element 2. The cover 5 is provided with a thermometer 25 which serves as a guide when adjusting the switch to actuate at a desired temperature.

Screw holes 26 may be provided in the frame 4 for mounting the device upon a wall or partition surface.

In Fig. 4, the device is shown mounted in a modified form of casing. The casing here consists of a body portion 27 and a cap portion 28 having a flange 29, which is intended to be mounted flush with a wall surface.

In Fig. 5, the device is shown mounted in another modified form of casing, comprising a rear enclosing frame 30, a mounting plate 31, and a cover portion 32. The rear frame 30 constitutes a weather-proof connection box for the electrical leads and is provided with a threaded opening 35 for a conduit connection.

In Figs. 6 and 7, a modified structure is shown in which a cylindrical contactor tube 36 is used. The tube 36 is designed to be normally located in a position neighboring the horizontal and upon being tilted, a body of mercury 37 is designed to flow into and out of bridging relation with a pair of electrodes 38 and 39 which are connected in circuit in the manner of electrodes 7 and 8 above described. A contactor tube of this type has been found to be accurately responsive to very slight changes in its angular position and consequently is desirable for use where only small changes in temperature 100 occur. The tube 36 is mounted upon a spiral element 40 by means of a spring clip 41. It will be noted that the spiral element 40 is shown in an inverted position from that shown in Fig. 1, in order to accommodate 110 more readily the cylindrical type of contactor tube. The spiral element 40 is attached by means of rivets 42 to a supporting arm 43.

In Fig. 8, a further modification is shown 120 in which a hollow spiral thermostatic element 44 is used. The hollow portion of this spiral element may form a continuous passage throughout the length of the spiral and may be connected at an end, if desired, with a container 45. The passage through the spiral element and the container 45 may be filled with air or other fluids, which when heated will result in a change in pressure. This pressure change will serve to alter 125

the shape of the spiral element 44 and thus actuate the contactor tube. It will be understood that container 45 is merely disclosed as an example of a source of pressure changes

5 and that the contactor tube and spiral element shown in Fig. 8 are capable of use with, and may be actuated by, other desired sources of varying pressure.

In Fig. 9, a modification is shown embodying features shown in Figs. 3 and 8. A hollow spiral element 46 is shown having outer and inner walls 46^a and 46^b composed respectively of materials having different coefficients of expansion. This spiral element 15 may also be attached to a source of variable pressure, such as the fluid container 47 and hence this element is subject to an alteration in shape when temperature changes occur, both because of its bi-metallic nature 20 and because of its action as a curved pressure tube.

In all of the above described structures it will be noted that the use of bearings in the operating parts of the mountings of the 25 contactor tubes is entirely eliminated. Consequently the spiral elements when actuating the contactor tubes, are not required to overcome any variable frictional losses as would result with the use of bearings.

30 The operation and one method of using the device of Fig. 1 will now be outlined. The binding posts 19 and 20 are connected directly in series with the circuit which is to be controlled such, for example, as the 35 circuit of a motor controlled heating equipment of any of the usual and suitable types.

Assuming that the room temperature is at or near the desired point, the lever 13 is turned so that the contactor tube 1 is 40 in a substantially neutral position ready to either close or open the circuit with a very slight change of temperature. If it is assumed that the device is being used for the regulation of heating equipments and that 45 the room is at the desired temperature, then the heating apparatus should not be in full operation and consequently the contactor tube should be in open circuit position with the body of mercury 9 out of contact with the electrode 7. However, as the room temperature drops a predetermined amount, the 50 thermostatic element 2 will become modified in shape because of the temperature change and will rotate the contactor tube 1 about its axis into circuit closing position.

The current to the contactor tube will now flow through the spiral element 2 and will start the operation of the heating equipment. The spiral element 2 will thereupon begin 60 to return to its normal position and will begin to rotate the contactor tube back to its former position as a result of two causes: first, the heating equipment will have partially restored the room temperature and 65 second, the current running through the

spiral element will furnish a slight amount of heat, thus aiding in quickly bringing the temperature of the spiral element 2 back to normal.

This current heating effect obtaining in 70 the element 2 has a particular advantage in this type of heat regulating switch which will now be outlined. When the contactor tube 1 turns to its closed circuit position it will tend to remain there for a slightly 75 longer period than necessary due to inertia of the heating apparatus and to the time required to bring the room temperature and the temperature of the thermostatic element back to normal. This will result in a room 80 temperature considerably in excess of that desired before the thermostatic element is sufficiently heated to cause the heating equipment to be shut off. Hence, in order to use this type of regulating switch where 85 the temperature must be regulated very accurately, it is advisable to supplement the action of the increased room temperature upon the spiral element 2 with the heating action of the current flowing through this 90 element. With such a device it has been found possible to regulate the room temperature with an accuracy several degrees closer than with the former methods:

95 However, in case this type of thermostatic switch is used in connection with the control of refrigeration or cooling apparatus, it will ordinarily be connected in circuit and adjusted to open the circuit upon the occurrence of a sufficient drop in temperature. 100 This is the opposite of its action when used with heating apparatus where it serves to open the circuit upon the occurrence of a sufficient increase in temperature. In view of these facts, the heating effect of the current through the spiral element is unnecessary in the case of refrigeration and cooling apparatus. Consequently in the device as shown in Fig. 4, the current is not connected through the spiral element but independent 105 lead wires 16^a and 17^a are provided to the binding posts. In other instances it may be desirable to pass only a portion of the total current through the spiral element and in such cases a shunt wire 16^b, as shown in Fig. 110 5, may be so designed to by-pass the desired amount of current.

115 The terms "contactor", "liquid contactor" and "electrical contactor" as employed in the claims contained herein refer to the well 120 known type of mercury electric switch or an equivalent thereof which comprises an hermetically sealed container having electrodes disposed therein and a body of conducting liquid, such as mercury, which serves to 125 make and break the electric circuit between the said electrodes. The various modifications of our invention shown in the drawings are illustrative of several types of such contactors as are covered by our present in- 130

vention. It is obvious, therefore, that the above-mentioned terms do not pertain to an open and exposed contact member which is movable by the coiled thermostatic element and which is adapted to control an electric circuit by cooperating with a second and fixed open contact member.

While we have shown and described several embodiments of our invention, it is to be understood that many modifications may be made therein without departing from the spirit and scope of the appended claims, and we desire that only such limitations shall be imposed upon our invention as are specifically pointed out in the claims and such as are required by the prior art.

Having thus described our invention, what we claim as new and desire to secure by Letters Patent in the United States, is:

20. 1. A thermostatic switch comprising a coiled thermostatic element, a liquid contactor wholly supported on and movable with said element, a body of conducting liquid housed in said contactor, and an adjustable supporting means for said element for adjusting the position of said contactor.

30. 2. A thermostatic switch comprising a heat responsive element formed of conducting material, a liquid contactor comprising a container, cooperating electrodes sealed therein and a conducting body housed in said container, said contactor being wholly supported upon one end of said element, and an electrical circuit to said contactor connected through said element to one of said electrodes.

40. 3. A thermostatic switch comprising a heat responsive element formed of conducting material, a liquid contactor comprising a container, cooperating electrodes sealed therein and a conducting body housed in said container, said contactor being wholly supported upon a free end of said element, and an electrical circuit to said contactor connected through said element to one of said electrodes, whereby the current that may flow in said circuit serves to heat and thereby tends to actuate said element.

50. 4. A thermostatic switch comprising a thermostatic element, and an electrical liquid contactor, including co-operating electrodes of opposite polarity, said element being fixed at one end and free at its other end and said electrical liquid contactor being wholly supported upon said free end.

60. 5. A thermostatic switch comprising a coiled thermostatic element and an electrical liquid contactor including co-operating electrodes of opposite polarity, said element being fixed at one end and free at its other end and said electrical liquid contactor being wholly supported upon said free end, and means for adjusting the angular position of said element and said contactor.

65. 6. An electrical switch comprising a spi-

rally shaped tube filled with a fluid, and an electrical contactor, said tube being fixed at one end and free at its other end and said contactor being entirely mounted upon said free end.

70

7. A thermostatic switch comprising a coiled thermostatic element, a liquid contactor mounted on the inner end thereof, and supporting means fixed to the outer end of said element, said supporting means being in turn pivotally mounted in order to provide for adjustment of the angular position of the said liquid contactor.

75

8. A thermostatic switch comprising a coiled thermostatic element, a liquid contactor mounted on the inner end thereof, and adjustable supporting means having in turn a mounting pivoted substantially coaxially with said coiled element in order to provide for adjustment of the angular position of said liquid contactor.

80

9. A thermostatic switch comprising a heat responsive element, a liquid contactor operable upon being tilted and wholly supported on the free end thereof, and supporting means fixed to the other end of said element, said supporting means being pivotally mounted in order to provide for adjustment of the actuating position of said liquid contactor.

85

10. A thermostatically operated electric switch comprising a thermostatic element, a mounting to which one end only of said element is fixed, a tiltable contactor mounted and wholly supported upon the other end of said element, said contactor comprising a container, electrodes therein and a conducting body movable therebetween, and means for adjusting the tilting angle of said contactor.

90

11. A thermostatic switch comprising a heat responsive element in the form of a substantially conical spiral, the end of said element at the base of the conical spiral being fixed, and an electrical contactor wholly and tiltably supported upon the end of said element at the apex of the conical spiral.

95

12. A thermostatic electric switch comprising a coiled thermostatic element having only one of its ends fixed, a liquid contactor operable on being tilted and supported wholly upon the other end of said thermostatic element, and means for adjusting the angular position of said liquid contactor thereby permitting said thermostatic element to tilt said contactor at predetermined temperatures.

100

13. A thermostatic switch comprising a coiled thermostatic element having only one of its ends fixed, a liquid contactor operable on being tilted wholly carried by and mounted upon the free end of said thermostatic element, and means for adjusting the angular position of said liquid contactor to permit said thermostatic element to oper-

110

115

120

125

130

ate it at different predetermined temperatures.

14. An electrical device comprising a coiled thermostatic element, a mounting member, a bracket mounted on said mounting member and having one end only of said thermostatic element secured thereto, a liquid contactor operable on being tilted and mounted upon and carried by the free end 10 of said thermostatic element, said bracket being adjustable for varying the angular position of said liquid contactor thereby permitting said thermostatic element to operate said liquid contactor at predetermined 15 temperatures.

15. An electrical device comprising a spirally coiled thermostatic element, a mounting member, a bracket adjustably pivoted upon said mounting member, the outer 20 end of said thermostatic element being secured to said bracket, and a liquid contactor mounted upon and carried by the inner end of said thermostatic element at its axis.

16. An electrical device comprising a coiled thermostatic element, a mounting member, a bracket pivoted upon said mounting member, one end of said coiled thermostatic element being secured to said bracket, and a liquid contactor mounted 30 upon and carried by the free end of said thermostatic element.

17. An electrical device comprising a coiled actuating element, a mounting member, a bracket adjustably secured to said mounting member, one end of said element being secured to said bracket, and a liquid contactor wholly supported upon and carried by the free end of said element.

18. A thermostatic switch comprising a thermostatic coil, a mounting member, a bracket pivotally secured to said mounting member, the outer end of said coil being attached to said bracket, and a liquid contactor wholly supported upon the free end 45 of said coil.

19. An electrical device comprising a thermostatic spirally coiled element, a mounting member, a bracket pivoted thereto, the outer end of said element being attached 50 to said bracket, and a liquid contactor disposed at the axis thereof, said contactor being wholly supported upon the free end of said element.

20. A thermostatic switch comprising a

coiled actuating element, a liquid contactor 55 operable upon being tilted and mounted upon the free end of said coiled element adjacent to the axis thereof, and supporting means to which the other end of said coiled element is attached, said supporting means 60 being adjustable to provide for adjustment of the tilting angle of said contactor.

21. An electrical device comprising a thermostatic coil, a liquid contactor operable upon being tilted and mounted adjacent to 65 the axis thereof and wholly supported upon the free end of said coil, supporting means to which the other end of said coil is secured, said supporting means being adjustable in order to provide for varying the actuating 70 position of said contactor, and electrical connections for said contactor constituting said coil as a part thereof.

22. An electric switch comprising an actuating element having only one end thereof 75 fixed, a tiltable liquid contactor being mounted and wholly supported upon the free end of said element, said contactor comprising a container, electrodes therein and a conducting body movable therebetween, and means for adjusting said actuating element whereby the tilting angle of said contactor for opening and closing its associated electric circuit may be varied.

23. An electric switch comprising a heat responsive actuating element having only one end thereof fixed, a tiltable contactor mounted and wholly supported upon the free end of said element, said contactor comprising a container, electrodes therein and a conducting body movable therebetween, said heat responsive element serving to tilt said contactor under the influence of temperature changes to which it may be subjected.

24. A thermostatic switch comprising a 95 thermostatic element, a mounting to which only one end of said element is fixed, a tiltable contactor secured to and wholly supported upon the free end of said element, said contactor comprising a container, electrodes 100 therein, and a conducting body movable therebetween, and means for adjusting said thermostatic element whereby the tilting angle of said contactor may be varied.

In witness whereof, we have hereunto subscribed our names.

LOUIS A. M. PHELAN.
CLIFFORD HOTCHKISS.
